UNITED STATES PATENT OFFICE

WILLIAM PAUL RUDKIN, OF OKLAHOMA CITY, OKLAHOMA, ASSIGNOR OF ONE-HALF
TO ALFRED BENJIMAN CLAUSSEN, OF OKLAHOMA CITY, OKLAHOMA

AEROPLANE

Application filed September 28, 1929. Serial No. 395,831.

This invention relates to an improved form of aeroplane construction wherein a plurality of motor units are used which are so positioned with relation to the supporting surface 5 of the aeroplane, as will be hereinafter described, that sufficient vertical lift will be produced to obviate the usual preliminary run before take-off is accomplished, which preliminary run is so necessary with the usual 10 present day planes.

It is a well known fact that one of the greatest drawbacks to the field of aviation is the necessity of having large areas of ground to allow the planes to take-off and to land. The 15 landing speeds of most planes are seldom less than 40 to 50 miles per hour and consequently considerable room must be available to enable the plane to be gradually brought to a stop.

Further, these aeroplane fields have to be so 20 situated as to enable a plane to take-off or land in any direction, depending on the direction from which the wind is blowing, all of which greatly increases the difficulties of establishing a desirable field or airport.

The rapid increase in the use of aeroplanes 25 in transporting mail, passengers, and freight, within recent years, produces a situation which requires the airport to be as near the city as possible. As a rule, it is very expensive and exceedingly difficult to create these fields near the city because of the necessity of obtaining these large areas of ground which must be level to permit the landing and take-off of the large transport planes. Especially 30 is this true in the eastern part of this country, where the cities themselves are located on the level ground as much as possible and the surrounding territory is comparatively rough.

For these reasons it is highly desirable to 35 provide an aeroplane which requires very little landing and take-off space. To this end, I have provided a relatively simple construction for an aeroplane which will take-off or land substantially vertically.

A further object of my invention is to provide a means for maneuvering the plane by the simple expedient of varying the relative speeds of a plurality of motor units or by shifting the relative positions of the motor 40 units with respect to each other.

Another object of the invention is to provide a supporting surface for the plane which is so constructed as to enable the plane to gradually float downwardly, in the event all of the motors become disabled.

A still further object of the invention is to dispose a plurality of motor units so that air will be drawn in towards the center of the plane from all sides and then be caused to diverge to impinge against the under side of 55 the supporting surface and also creating a downward stream of air, each of which produces a lifting action on the plane.

Other and further objects and advantages of the invention will be hereinafter set forth 60 and the novel features thereof defined by the appended claims.

In the drawings:

Fig. 1 is a side elevation of one form of my 65 invention;

Fig. 2 is a sectional view taken on the line 70 2-2 of Fig. 1;

Fig. 3 is a side elevation of a modified form 75 of my invention;

Fig. 4 is a sectional view taken on the line 4-4 of Fig. 3; and

Fig. 5 is a fragmentary detail view of the 80 control mechanism for shifting the motor units.

Like numerals refer to like parts in the 85 several figures of the drawings.

Referring to Figs. 1 and 2, 1 denotes the supporting surface for the aeroplane, being of a concave formation and constructed of any suitable material such as that used in 85 the usual types of aeroplane wing constructions. A supporting frame 2 is connected to the supporting surface 1 and carries at its lower end the fuselage or cabin 3 of any desired form and having any suitable landing gear, such as the wheels 4, and members 5 connecting the same to the fuselage. A rudder 6 is also provided to assist in stabilizing the plane during flight.

Intermediate the supporting surface and 90 the fuselage or cabin and connected to the supporting frame are the motor units or propelling units 7 which may be of any desired type and having the usual type of propeller. These motor units are preferably located op- 100

posite each other so as to draw the air from all directions horizontally below the supporting surface.

The streams of air from each propeller converge at the center where it is caused to split into two streams, one of which is directed vertically upward against the under side of the supporting surface 1, the other air stream being directed downwardly into the surrounding atmosphere. Both of these air streams will exert a vertical lift on the aeroplane, thus enabling it to rise from the ground without any preliminary run.

Obviously, any number of motors may be employed nor do they have to be an even number as long as they are arranged radially with respect to the supporting surface 1 and spaced equidistant.

To cause the aeroplane to travel in a horizontal direction after having risen to the desired altitude, it is only necessary to speed up the motor on that side in the direction of which it is desired to travel. The rudder permits variations in the direction of travel, although this might be dispensed with and the speeds of the other motors varied to change the direction.

It will be seen that the plane may be maneuvered in any direction and that it can be held practically stationary in the air by properly controlling the speed of the motors. Also, if all of the motors become disabled, the plane will gently float down in a manner similar to a parachute, owing to the concave formation of the supporting surface 1.

Referring to the modified form of my invention as shown in Figs. 3 to 5, 1' denotes an elongated supporting surface which is also concave and from which is suspended the supporting frame 2', at the lower end of which is connected the cabin or fuselage 3' having a rudder 6'. In this form, the motor units 7' are supported on a horizontal framework 8 and are arranged in rows on opposite sides thereof. The motors are preferably carried in a frame 9 having vertical pivots 10 rotatably mounted in the brackets 11 secured to the horizontal framework 8. Extending inwardly from the rear of each motor is a telescopic connection 12 to which a common operating rod 13 is pivoted. This operating rod is controlled in any suitable manner from the fuselage of the plane, such as for example by the rack 14 and pinion 15 which is carried by the shaft 16 extending upwardly from the fuselage.

Normally, the motors on each side are positioned outwardly 180° from the motors on the other side, such a position causing the air to be drawn inwardly in streams which meet at the center and are caused to diverge into an upward vertical stream impinging against the supporting surface 1', and a downward stream into the atmosphere as in the form described with respect to Figs. 1 and 2.

Manipulation of the operating rod 13 shifts the motor units simultaneously on their pivots 10, as shown by the dotted lines in Fig. 5, thereby creating a longitudinal pull which will cause the plane to travel in a longitudinal or horizontal direction. Varying the speed of each motor at will permits the plane to be maneuvered as in the first form of construction. Angular shifting of the motor units, besides varying the longitudinal or horizontal pull, also varies the vertical lifting action, owing to the angle at which the air streams from each side meet at the center.

Suitable means for controlling the speed of the motors from the fuselage, such as for example by the cables 17 in Figs. 1 and 2 and 17' in Figs. 3 to 5, may be employed. I also do not wish to be limited to the particular form of fuselage as shown in the drawings, for obviously this may be of any desired shape and may be equipped with wheels or pontoons for landing on land or water, or the fuselage itself may be such as to permit landing on water without pontoons.

While the specific details of construction have been herein shown and described, the invention is not confined thereto, as changes and alterations may be made without departing from the spirit thereof, as defined by the appended claims.

Having thus described my invention, what I claim as new and desire to secure by Letters Patent is:

1. An aeroplane of the class described comprising a supporting surface, a fuselage connected thereto, oppositely disposed horizontal motor units located beneath said supporting surface for producing vertical streams of air in opposite directions to effect a lifting action, and means for varying the relative positions of the said motor units to vary the lifting action.

2. An aeroplane of the class described comprising a supporting surface, a fuselage connected thereto, oppositely disposed horizontal motor units located beneath said supporting surface for producing vertical streams of air in opposite directions to effect a lifting action, and means for varying the relative positions of the said motor units to vary the lifting action, said means being operable from within the fuselage.

3. An aeroplane of the class described comprising a supporting surface, a fuselage associated therewith, a plurality of motor units intermediate said fuselage and said supporting surface, and means for varying the relative angular positions of said units with respect to each other.

In testimony whereof I affix my signature.

WILLIAM PAUL RUDKIN.
